UNITED STATES PATENT OFFICE.

PERCY W. ELLIS, OF DENVER, COLORADO.

CAR-SEAL.

No. 912,947.

Specification of Letters Patent.

Patented Feb. 16, 1909.

Application filed April 6, 1908. Serial No. 425,378.

To all whom it may concern:

Be it known that I, PERCY W. ELLIS, a citizen of the United States, residing in the city and county of Denver and State of Colorado, have invented certain new and useful Improvements in Car-Seals; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in car seals, my object being to provide a device of this class which shall be simple in construction, economical in cost, reliable, durable and efficient in use, and to this end the invention consists of the features hereinafter described and claimed, all of which will be fully understood by reference to the accompanying drawing in which is illustrated an embodiment thereof.

In this drawing, Figure 1 is a perspective view of my improved car seal shown in the unlocked position. Fig. 2 is a top plan view showing the casing in horizontal section, the parts being in the unlocked position. Fig. 3 is a similar view showing the parts in their locked position. Fig. 4 is a vertical longitudinal section taken through the device showing the same in the unlocked position. Fig. 5 is a similar view showing the parts in the locked position. Fig. 6 is an underneath view of the device, shown in the locked position. Fig. 7 is a top view of the same. Fig. 8 is a fragmentary sectional view similar to Fig. 4 but showing the parts on a larger scale. Fig. 9 is a similar view showing the parts in the locked position. Fig. 10 is a perspective view in detail of the locking dog. Fig. 11 is an extended view of the flexible strip or sealing strip shown in detail.

The same reference characters indicate the same parts in all the views.

Let the numeral 5 designate a casing in which the sealing strip is anchored said strip being bent at 6 and provided with upper and lower members 7 and 8 located within the casing. This casing is bent below the member 8 and secured thereto in any suitable manner (see Fig. 6). The two members 7 and 8 are separated, the member 8 being provided with a slot 9 in its front portion and an opening 10 in its rear portion. The locking dog 12 which is also located within the

casing, consists of a forwardly located plate 13 having an upwardly projecting tooth 14 and a rearwardly projecting member 15 having a downwardly projecting tooth 16 located at its rear extremity. The part 15 is connected to the plate 13 by an upwardly projecting part 17. When the parts are assembled, the plate 13 of the dog rests upon the member 8 of the sealing strip within the casing, while the part 15 occupies a position above the member 7, the upwardly projecting part 17 occupying a position within the slot. It will be observed that the part 13 is below the member 7 of the sealing strip while the part 15 is above said member when the parts are in the assembled position and before the locking operation.

As shown in the drawing the bottom of the casing is flat while its top is provided with a channel which is downwardly inclined from the forward to the rear portion of the casing. When the parts are in the unlocked position, the member 15 of the dog, protrudes into this channel and engages the top thereof at a point forward of the opening 10. The forward extremity of the casing is provided with a slot 20 adapted to receive the free extremity 21 of the sealing strip, the same being provided with an aperture 22.

Assuming that the parts are assembled as shown in Figs. 2, 4 and 8 of the drawing, if it is desired to lock the seal, the free extremity 21 is inserted in the slot 20 of the casing and the free extremity moved rearwardly. This free end of the strip first comes in contact with the upwardly projecting part or offset 17 of the member 15, and as the said end is moved rearwardly, the dog is carried in the same direction, its rear extremity being forced downwardly by the downward inclination of the top of the casing above the channel 18. During this rearward movement of the dog, the member 7 of the sealing strip is bent downwardly until the tooth 16 of the dog reaches the opening 10 which it enters and moves downwardly giving a tilting movement to the dog whereby the forward extremity of the part 15 is caused to engage the top wall of the casing above the channel 18, while the forward extremity of the dog moves upwardly, causing the tooth 14, to enter the aperture 22 in the free extremity of the sealing strip, and also the slot 9 in the forward portion of the yielding support 7 since the forward extremity of this support is also in position to receive the said

tooth thus producing a double locking effect since the removal of the free extremity of the sealing strip from the casing is resisted by the engagement of both teeth of the dog or locking device with the yielding support. Simultaneously with this movement of the locking dog, the rear portion of the member 7 of the strip within the casing springs upwardly whereby this member cooperates with the 10 rearward tooth 16 of the dog to bring about the locking result. It will thus be observed that the free extremity 20 of the sealing strip is securely locked in place within the casing and cannot be removed without 15 mutilating the device and leaving evidence that the seal has been tampered with.

Having thus described my invention, what I claim is:

1. A car seal provided with a casing, a 20 sealing strip attached to the casing, a support within the casing comprising a slotted spring member, a locking device having oppositely projecting teeth at its opposite extremities, and an intermediate offset passing 25 through the slot of the spring member, the rearward tooth of the locking device engaging the spring member from above, the latter being provided with an opening in the rear of the slot adapted to receive said tooth, the free 30 extremity of the sealing strip having an opening adapted to be engaged by the forward tooth of the said device when the latter is moved rearwardly to the locking position, the casing above the locking device being 35 downwardly inclined as it extends rearwardly and engaging the locking device from above, substantially as described.

2. A seal comprising a casing, a sealing strip secured to the casing, a yielding support 40 located within the casing and extending above the bottom of the same, the said support having a slot in its forward portion and an aperture in the rear of the slot, a locking device having teeth at its opposite extremities, and an intermediate offset passing 45 through the slot of the yielding support, the upper extremity of the casing being in contact with the locking device, the forward extremity of the casing being provided with 50 a slot to receive the free extremity of the sealing strip which is provided with an opening to receive the tooth on the forward extremity of the locking device when the latter is moved rearwardly sufficiently to cause its 55 rearward tooth to engage the aperture in the yielding support, substantially as described.

3. A self locking seal comprising a casing, a sealing strip having one extremity secured to the casing, a yielding support within the 60 casing provided with a forward slot and a rearward aperture, a rigid locking device passing through the slot of the yielding support and having teeth at its opposite extremities, the forward extremity of the casing being 65 open to receive the free extremity of the

sealing strip which is provided with an opening, the locking device within the casing having a part adapted to be engaged by the free end of the sealing strip as the latter is inserted in the casing and moved rearwardly, the locking device having sufficient movement to allow the teeth at its opposite extremities to enter the respective openings in the yielding support and the free extremity of the sealing strip, substantially as de- 75 scribed.

4. The combination with a casing, of a sealing strip having one extremity connected with the casing, a yielding support within the casing having a slot in its forward portion and a rearwardly located aperture, a locking device having teeth at its opposite extremities, and an intermediate offset adapted to engage the slot in the yielding support, whereby the forward portion of the locking device occupies a position below the yielding support while its rear extremity occupies a position above the same, the upper wall of the casing being downwardly inclined as it extends rearwardly and in contact with the locking device as the latter is moved rearwardly, the casing having an opening to receive the free extremity of the sealing strip which is also provided with an aperture, the offset of the locking device lying in the path 90 of the free end of the sealing strip as the latter is inserted in the casing and moved rearwardly, the degree of movement being such as to allow the teeth at the opposite extremities of the locking device to engage the respective openings in the yielding support and the free extremity of the sealing strip, substantially as described.

5. The combination with a casing, of a sealing strip having one extremity secured to the casing, a yielding support also located in the casing and provided with a slot in its forward portion and an opening in its rear portion, a rigid locking device having oppositely projecting teeth at its opposite extremities and having an intermediate offset which engages the slot of the yielding support whereby the rear portion of the said device is above the support and its forward portion below the same, the upper surface of the casing being downwardly inclined as it extends rearwardly whereby as the locking device is moved rearwardly the spring support is forced downwardly until the tooth at the rear extremity of the locking device is in position to engage the rearward aperture of the spring support, substantially as described.

6. A self locking seal comprising a casing, a sealing strip having one extremity attached to the casing, a spring support having a rearwardly located opening, a rigid locking device engaging the spring support and having a tooth at its rear extremity, the upper part of the casing being in engagement with 125

the locking device and downwardly inclined as it extends rearwardly whereby as the locking device is moved rearwardly upon the support, the said device is forced downwardly until the tooth at its rear extremity is in position to engage the opening in the spring support, substantially as described.

7. The combination with a casing whose upper surface is downwardly inclined from 10 its forward extremity, a sealing strip attached to the said casing, a spring support located within the casing and having an elongated opening in its forward portion, and a rearwardly located aperture, a locking 15 device having teeth at its opposite extremities, and an intermediate offset adapted to engage the slot of the support to allow the locking device to be moved rearwardly, the upper side of the casing engaging the 20 locking device and causing it to depress the spring support as the said device is moved rearwardly, until the rearward tooth of the said device engages the opening in the rear portion of the spring support, the free 25 extremity of the sealing strip being adapted to enter the forward extremity of the casing and actuate the locking device, the said extremity of the sealing strip having an opening to receive the forward tooth of the locking device simultaneously with the engagement of the latter's rearward tooth with the opening in the rear portion of the spring support, substantially as described.

8. In a self locking seal, the combination 30 with a casing, of a sealing strip having one extremity secured to the casing, a spring support within the casing and having a slot in its forward portion and an aperture in the rear of the slot, a rigid locking device having 35 a part passing through the said slot whereby its forward portion is below the support and its rear portion above the same, the locking device having teeth at its forward and rear extremities, the free extremity of the sealing 40 strip having an opening, the forward extremity of the casing having a slot to receive said strip, the locking device being located

to engage the free end of the said strip as the latter is inserted in the casing and moved rearwardly, the locking device having sufficient rearward movement to allow its rearward tooth to engage the aperture in the rear portion of the support and its forward tooth to engage the aperture in the free extremity of the sealing strip, the support 50 being also in position to allow the last named tooth to enter the forward extremity of its slot which registers with the opening in the free extremity of the sealing strip, substantially as described. 55

9. The combination with a casing, of a sealing strip connected with the casing, a spring support within the casing, a rigid locking device having teeth at its opposite extremities and an intermediate offset, the 60 support having a slot in its forward portion, and an aperture in the rear thereof, the offset of the locking device passing through the slot of the support, and means for actuating the locking device in a rearward direction 65 to cause its rearward tooth to enter the aperture in the support and its forward tooth the slot in the support, substantially as described.

10. The combination with a casing, of a sealing strip having one extremity attached 70 to the casing, a spring support within the casing having a slot in its forward extremity and an aperture in the rear of the slot, a rigid locking device having an offset intermediate its extremities engaging the slot of 75 the support, the said device also having teeth at its opposite extremities, the free end of the sealing strip having an aperture and adapted to enter the casing and move the locking device rearwardly until the rear tooth of the 80 latter engages the aperture in the support and the forward tooth the aperture of the sealing strip and the slot of the support.

In testimony whereof I affix my signature in presence of two witnesses.

PERCY W. ELLIS.
